UNITED STATES PATENT OFFICE

WALTER WILLIAM LARGE AND REGINALD HERBERT TAPPER, OF CALGARY,
ALBERTA, CANADA.

FENCE-POST.

1,013,026.

Specification of Letters Patent. Patented Dec. 26, 1911.

Application filed September 30, 1911. Serial No. 652,102.

To all whom it may concern:

Be it known that we, WALTER WILLIAM LARGE and REGINALD HERBERT TAPPER, subjects of the King of England, residing at 5 Calgary, Province of Alberta, and Dominion of Canada, have invented certain new and useful Improvements in Fence-Posts, of which the following is a specification, reference being had to the accompanying drawings.

This invention relates to fence posts and more particularly to one formed entirely from metal.

The invention has for its object to provide a post of this character so constructed that the line wires forming a fence may be easily and quickly strung and adjusted.

A further object of the invention is to produce a fence post which is simple in construction and will withstand all conditions of weather, the life of the same being indefinite.

A still further object of the invention is to provide a post upon which either a fabric or line wires may be firmly clamped and supported in a simple and effective manner.

In the accompanying drawings: Figure 1 is a front elevation of the post; Fig. 2 is a longitudinal sectional view of the same; Fig. 3 is a sectional view on the line 3—3 of Fig. 1; Fig. 4 is a perspective view of one of the securing devices. Fig. 5 is a section similar to that shown in Fig. 3 but indicating a hollow form of post.

Referring to the drawing the numeral 1 designates the metallic post, the same being substantially circular in cross section, the lower end of which is tapered and jagged, as is clearly shown at 2 to permit the post to be driven into the ground, easily, and at the same time keep it securely in position. A longitudinal slot 3 is formed through the post and intermediate the point 2 and the upper end thereof. The slot 3 opens into a longitudinal recess 4, the bottom walls of which are serrated, as indicated at 5 in the drawings, the purpose of which will be hereinafter described.

A series of securing devices 6 are employed and consist of heads 7 having formed

integrally therewith hooks 8, the inner surfaces of the heads being provided with serrations 9 which are adapted to conform with the serrations formed in the recess 4. The securing devices 6 further consist of threaded shanks 10, said shanks being adapted to pass through the slot 3 formed in the post to receive clamping nuts 11.

Formed integral with the post 1 and upon opposite sides thereof are ears 12, and to which the upper ends of brace bars 13 are secured, the lower ends of which being adapted to be suitably anchored to brace the post.

The line wires 14 are passed through the hooks 8 of the securing devices, and upon manipulation of the clamping nuts 11 said wires will be crimped to conform to the recess 3, and securely held against creeping.

From this construction it will be seen that the line wires may be spaced properly upon vertical adjustment of the securing devices 6, the same being held firmly against vertical movement or displacement by the co-acting serrations.

Having thus described the invention, we claim:—

The combination of a fence post having a longitudinal slot, said slot opening into a recess, said recess having its bottom walls serrated, securing devices adapted for vertical adjustment in the recess, said devices consisting of heads having formed integral therewith hooks, serrations formed upon the inner surfaces of the heads and adapted to conform with the serrations in the recess, threaded shanks carried by the heads and adapted to pass through the slot, and means carried by the shanks for clamping the securing devices in their adjusted positions in the recess, whereby the line wires of a fence are secured by said hooks.

In testimony whereof we hereunto affix our signatures in the presence of two witnesses.

WALTER WILLIAM LARGE.

REGINALD HERBERT TAPPER.
